Ohio, assignors to The Tappan Stove Company,
Mansfield, Ohio, a corporation of Ohio

Application December 11, 1950, Serial No. 200,201

7 Claims. (Cl. 137—576)

1

This invention relates to an electrically operated safety control valve mechanism which is especially adapted for use in automatic ignition and control systems for the oven burners of cooking ranges using gaseous fuel. It may be used equally well in systems having a time control mechanism incorporated therein, and in systems in which no time control is provided.

The mechanism is designed for use in automatic ignition and control systems in which the main burner is ignited by an associated pilot burner which must burn constantly all of the time the main burner is turned on. The pilot burner is ignited by an electrical resistance ignition element which is automatically de-energized after the pilot burner has been ignited.

In most cooking ranges in use today it is immaterial whether or not the oven burner burns constantly as long as the pilot burner associated therewith is ignited. It may be extinguished for some reason but it will be promptly reignited by the pilot burner if fuel is supplied thereto. But if the pilot burner is extinguished for any reason while the main control valve is still open to supply gas to the main burner a very dangerous situation sometimes arises. Let us assume that both the pilot burner and the main burner are extinguished during operation for some reason. Gas can then flow to the main burner but since the pilot burner is extinguished the main burner will not be ignited and unburned gas will accumulate in the oven which may violently explode when an attempt is made to ignite either the main or pilot burner. It has been found by experience that both the pilot burner and the main burner are frequently extinguished during use while the main control valve is open to supply gas to the main burner. This is sometimes due to a momentary failure of the gas supply or the slamming of the oven door or to various other reasons.

In order to prevent an accumulation of unburned gas and thus eliminate danger of an explosion therefrom in the event the pilot burner is extinguished for any reason while the control valve is still open to supply gas to the main burner, we provide our improved safety control valve mechanism by which the supply of gas to the main burner is cut off independently of the main control valve, in the event the pilot burner is extinguished for any reason while the main gas control valve is open.

We have shown our improved valve mechanism incorporated in an automatic ignition and control system which includes a main gaseous fuel burner by which the oven in a cooking range is heated. The main burner is adapted to be ignited by a gaseous fuel pilot burner which burns only during the time the oven is in operation. At other times the supply of gas to both

5 the main burner and the pilot burner is cut off by a main control valve which is interposed in a conduit between the gas supply manifold and the burners. When the main control valve is open gas will flow from the main control valve and into our improved safety control valve mechanism. From the safety control valve mechanism gas will flow through a small branch conduit directly to the pilot burner; and through the main conduit and a standard thermostatically operated oven temperature control valve to the main burner. A normally open master control switch which is operatively associated with the main control valve is arranged to be closed by the opening of the main control valve and to be opened by the closing of the main control valve. The closing of the master control switch, as the main control valve is opened to supply gas to the burners, energizes through a normally closed thermostatically operated switch an electric resistance ignition element and a solenoid which is operatively connected to the safety control valve mechanism. The energization of the solenoid causes it to operate the safety control valve mechanism to permit the flow of gas to the pilot burner while cutting off the supply of gas to the main burner. The pilot burner is then ignited by the electric ignition element and projects a flame against a thermostatic element, 10 which controls the operation of the normally closed switch, and against a thermocouple which is in circuit with an electromagnet in the safety control valve mechanism. After the thermostatic element becomes heated it opens the normally closed switch which de-energizes the electric ignition element and the solenoid. As soon as the solenoid is de-energized the safety control mechanism is automatically operated by spring means to supply gas to the main burner through the oven temperature control valve. The main burner is then ignited by the pilot burner. The thermocouple, as long as it is heated by the pilot burner, maintains the safety control valve mechanism through the electromagnet in condition to supply gas to both the main burner and the pilot burner. The oven temperature control valve then regulates the supply of gas to the main burner so as to maintain the desired oven temperature. As long as the pilot burner is ignited the main burner will burn normally under the control of the oven temperature control valve until the main control valve is manually turned off. But if during operation the pilot burner is extinguished for any reason the thermocouple will immediately cool and cause the safety control valve mechanism to automatically cut off the supply of gas to both the main burner and the pilot burner. As an example of the manner of operation of the apparatus, let us assume that during operation

the pilot burner is suddenly extinguished, for instance, by a momentary failure of the gas supply from the manifold to the burners. The thermocouple immediately cools, causing the safety control valve mechanism to cut off communication between the manifold and both the main burner and the pilot burner. The main control valve is still open and the master switch closed. Then after the thermostatic element has cooled, closing the normally closed switch, which is maintained open by the thermostatic element during normal operation of the oven, the electric ignition element and the solenoid are again energized. The energization of the solenoid will cause it to operate the safety control valve mechanism to re-establish communication between the manifold and the pilot burner only. Then when gas is again available the pilot burner will be ignited and reestablish normal operation of the oven as previously described. In the event of a power failure during normal operation of the oven, the main burner will continue to operate normally under the control of the oven temperature regulator valve until the burner is turned off by the main control valve, assuming of course that the pilot burner continues to burn. In the event of a power failure before gas is turned on by the main control valve, the pilot burner can be manually ignited, as will be hereinafter explained. The supply of gas to both the main burner and the pilot burner will then be controlled by the pilot burner through the thermocouple and safety control valve mechanism as previously described.

In order to accommodate the apparatus for use in conjunction with any standard type time control mechanism, we provide a supplemental master switch and a normally open solenoid valve. The supplemental master switch is inserted in the main circuit in series with the primary master switch and is adapted to be closed at a predetermined time by the time control mechanism. The normally open solenoid valve is inserted in the branch conduit between the safety control valve mechanism and the pilot burner, and is adapted to be closed at a predetermined set time by the time control mechanism. In use the time control mechanism is set to initiate operation of the oven burner at a predetermined time and to terminate operation thereof at a predetermined later time, after the main control valve has been turned on which also closes the primary master switch. Then when the supplemental switch which is in series with the primary switch is closed by the time control mechanism the apparatus will function in the same manner as previously described, until the time control mechanism effects the closing of the normally open solenoid valve which cuts off the supply of gas to and extinguishes the pilot burner which in turn causes the safety control valve mechanism to operate to cut off the supply of gas to and thus extinguish the main burner. Means to lock the supplemental switch closed is provided in order that the apparatus may be used independently of the time control mechanism when desired.

The principal object of the invention is to provide an improved electrically operated safety control valve mechanism for use in automatic electric ignition and control systems for gas ranges.

Another object of the invention is to provide a valve mechanism of this character which is very efficient in operation and yet is of very

simple construction and which can be easily and inexpensively manufactured.

Other and more limited objects of the invention will be apparent from the following specification and the accompanying drawings forming a part thereof in which:

Fig. 1 is a diagrammatic layout showing our improved safety control valve mechanism incorporated in an automatic electric ignition and control system for the oven burner in a cooking range;

Fig. 2 is an enlarged central longitudinal vertical section through the safety control valve mechanism showing the various parts in the 15 positions they assume when the oven burner is turned off;

Fig. 3 is a view similar to Fig. 2 showing the various parts in the positions they are automatically moved to when the main control valve is first turned on to initiate the operation of the main oven burner;

Fig. 4 is a horizontal section taken on the line 4—4 of Fig. 2;

Fig. 5 is a horizontal section taken on the line 25 5—5 of Fig. 2, and

Fig. 6 is a wiring diagram of the system as used in conjunction with a time control mechanism.

Referring now to the drawings by reference characters, the numeral 1 indicates a gaseous fuel burner which is mounted in or in heating relation to a cooking range oven 2. Gaseous fuel is supplied to the burner 1 from a manifold M through a conduit 3. Interposed in the conduit 3 are a main control valve 4, our improved safety control valve mechanism generally indicated by the numeral 5, and an oven temperature control valve 6. The main control valve 4 is a cut-off valve of standard construction which when in open or on position permits the flow of gas through the conduit 3 from the manifold to the burner 1, and in closed or off position cuts off the flow of gas to the burner 1. This valve is manually opened and closed by a handle 7 and a valve stem 8, and directly controls the operation of the entire system in that it initiates the operation of the entire system when it is turned to the on position and terminates the operation when it is turned to the off position. From the main control valve 4 gas flows through a connector 9 to the safety control valve mechanism 5, to be described in detail hereinafter. From the safety control valve mechanism 5 the gas flows through a connector 10, the oven temperature control valve 6 and the conduit 3 to the burner 1. The oven temperature control valve 6 is operative to regulate the amount of gas flowing to the burner 1 in order to maintain the oven at any desired set temperature. The valve 6 is set to any desired temperature by a handle 11 having a pointer 12 which cooperates with a graduated dial 13 carried by the valve 6. The valve 6 is controlled according to the temperature setting by a thermostatic element 14 which is mounted in the oven 2 and is connected to the valve 6 as shown at 15. The oven temperature control valve 6 is of standard well known construction. Consequently it is not shown in detail herein. There are many different constructions available, any one of which will work equally well herein. Gas is also supplied to a pilot burner 16 through a branch conduit 17 which extends between the safety control valve mechanism and the pilot burner 16. A normally open solenoid valve V which is adapted to be closed by its solenoid S

is interposed in the branch conduit 17 between the safety control valve mechanism 5 and the pilot burner 16 for a purpose to be hereinafter described. The solenoid valve V is of standard well known construction. Consequently it is not shown in detail herein. The pilot burner 16 is disposed adjacent the rear end of the main burner 1 in position to ignite the burner 1 when gas is supplied thereto. An electrical ignition element 18 is operatively associated with the pilot burner 16 in position to ignite the pilot burner 16 when gas is supplied thereto. A thermostatic element 19 and a thermocouple 20 are mounted in position to be heated by a flame from the pilot burner. The thermostatic element 19 is operative to open and close a switch 21 which controls the energization of the electrical ignition element 18 and a solenoid 22 which when energized operates the safety control valve mechanism to supply gas to the pilot burner 16, as will be described in connection with the description of the safety control valve mechanism and the operation of the whole apparatus. The thermocouple 20 when heated is operative to hold the safety control valve mechanism in condition to maintain the supply of gas to both the pilot burner 16 and the main burner 1, as will also be described in connection with the description of the safety control valve mechanism and the operation of the apparatus. A master switch 23 which is associated with the main control valve 4 is adapted to be opened and closed simultaneously with the closing and opening of the main control valve 4. As the control valve 4 is turned from the off or closed position to the on or opened position the switch 23 is moved from the open position to the closed position by an operating lever 24 which cooperates with a cam section 25 on the main control valve stem 8. Conversely, when the main control valve 4 is turned from the open or on position to the closed or off position the switch 23 is moved from the closed position to the open position. An electric circuit between the thermocouple 20 and the safety control valve mechanism 5 is established by a copper tube 26 which encloses an insulated wire 27. The ignition and control system just described per se constitutes no part of the subject matter of this application but is claimed in our co-pending applications Serial Nos. 153,664 and 163,764, filed April 3, 1950, and May 23, 1950, respectively.

The construction of the safety control valve mechanism 5 which constitutes the subject matter of this application will now be described, reference being had to Figs. 2 to 5 of the drawings. This mechanism comprises two opposed cup shaped casings 30 and 31 having outwardly extending complementary annular flanges 32 and 33 around the open ends thereof. A partition 34 is clamped between the casings 30 and 31 by bolts 35 which extend through aligned apertures in the flanges 32 and 33 and the partition 34. Gaskets 36 are interposed between the partition 34 and the flanges 32 and 33 to insure gas tightness. The upper casing 30 has a transverse partition 37 formed integral therewith which provides two chambers 38 and 39 in the upper casing. A single chamber 40 is provided in the lower casing 31. Communication between the chambers 38 and 40 is established by a passageway 41 in the partition 34, and between the chambers 39 and 40 by a passageway 42 in the partition 34. The passageway 41 is adapted to be closed by a valve 43 which seats in a valve

seat 44 around the upper end of the passageway 41, and the passageway 42 is adapted to be closed by a valve 45 which seats in a valve seat 46 around the upper end of the passageway 42. The valve 43 is guided in its movement by a valve stem 47 which is secured thereto and is slidably mounted in aligned bores in a sleeve 48 and a boss 49 within the chamber 40. The sleeve 48 is held in axial alignment with the passageway 10 41 by a spider 50 secured to the underside of the partition 34, and the boss 49 is formed integral with the bottom wall of the casing 31. The valve 45 is guided in its movement by a valve stem 51 which is secured thereto and is slidably mounted in aligned bores in a sleeve 52 and a boss 53 within the chamber 40. The sleeve 52 is held in axial alignment with the passageway 42 by a spider 54 secured to the underside of the partition 34, and the boss 53 is formed integral with the bottom wall of the casing 31. Vent holes 55 are provided to prevent gas being trapped under the valve stems 47 and 51. The valve 43 is adapted to be raised from its seat 44 to open the passageway 41, and the valve 45 is adapted to be simultaneously lowered to its seat 46 to close the passageway 42 by a lever 56 which is pivoted at 57 between ears 58 on the lower ends of a stud 59 which is formed integrally with and extends down into the chamber 40 from the underside of the partition 34. One end of the lever 56 is bifurcated as indicated at 60 and straddles the valve stem 47. The stem 47 is connected to the lever 56 by a pin 61 which is carried by the bifurcated end 60 of the lever 56 and extends through an elongated slot 62 in the valve stem 47. The valve stem 51 extends through an elongated aperture 63 in a widened section of the lever 56 and is connected to the lever 56 by a pin 64. The other end of the lever 56 is bifurcated as indicated at 65 and straddles the upper end of the core 66 of the solenoid 22. The lever 56 is connected to the upper end of the core 66 by a pin 68. The solenoid 22 which is secured to the upper side of the bottom wall of the casing 31 by any suitable means 69, will when energized shift the valves 43 and 45 from the position shown in Fig. 2 to the position shown in Fig. 3. A spring 70 disposed about the core 66 beneath a disc 71 carried by the core 66 is operative when the solenoid 22 is de-energized to return the lever 56 and valve 45 back from the position shown in Fig. 3 to the position shown in Fig. 2. The apertures in the lever 56 through which the pins 61, 64 and 68 extend are slightly elongated as indicated at 67 in order to prevent any binding when the lever 56 is rocked. An electromagnet 72 is secured to the inner end of a threaded hollow stud 73 within the chamber 38. The stud 73 extends out through an aperture, in the top wall of the casing 30, which is in axial alignment with the valve 43. The stud 73 and the electromagnet 72 are held in place by a nut 74. The legs of the electromagnet 72 have a winding 75 thereon, one end of which is connected to the tube 26 and the other end of which is connected to the wire 27 within the tube 26. The tube 26 is inserted into the hollow stud 73 and is held in place by a screw fitting 76. A port 79 in the casing 30 provides communication between the chamber 38 and the connector 9 to allow gas to flow from the main control valve 4 through the connector 9 and into the chamber 38. During normal operation of the main burner 1 gas flows from the chamber 38 through the passageway 41 into the chamber 40 and from the chamber 40

through the passageway 42 into the chamber 39. A port 80 which establishes communication between the conduit 17 and the chamber 40 is provided to supply gas to the pilot burner 16; and a port 81 establishes communication between the chamber 39 and the connector 10 to permit the flow of gas from the chamber 39 to the main burner 1 through the oven temperature control valve 6 and the conduit 3.

The master control switch 23 comprises the contacts 82 and 83 which are adapted to be bridged by the conductor bar 84; and the switch 21 comprises three contacts 88, 89 and 90, which are adapted to be bridged by a conductor bar 91 when the switch is in its normal closed position.

The supplemental master switch 92 which is shown in Fig. 6 comprises the contacts 93 and 94 which are adapted to be bridged by a conductor bar 95; and a switch 96 which is shown in Fig. 6 comprises the contacts 97 and 98 which are adapted to be bridged by a conductor bar 99. The contact 97 of the switch 96 is connected to the side 100 of the line by leads 101 and 102, and the contact 98 of the switch 96 is connected to one end of the winding 103 of the solenoid S by a lead 104. The other end of the winding 103 of the solenoid S is connected to the other side 105 of the line by leads 106 and 107. The switch 96 thus controls the energization of the solenoid S which when energized closes the normally open valve V. The conductor bars 95 and 99 are mounted on a base 108 of insulating material, which is adapted to be moved toward and away from the contacts 93, 94, 97 and 98 at predetermined times by a time control mechanism 109 through a connecting link 110. When it is desired to operate the oven burner independently of the time control mechanism, the switch 92 is locked in closed position and the switch 96 is locked in open position through the medium of a manually operable button 111 incorporated in the time control mechanism 109. The time control mechanism is of standard well known construction. Consequently it is not shown in detail herein. There are many different makes available, any one of which will work equally well herein.

The operation of the apparatus independently of the time control mechanism will now be described in connection with Fig. 6. To initiate the operation of the oven burner 1 it is only necessary to set the oven temperature control valve 6 to the desired temperature and to manually turn the main control valve 4 from the off position to the on position. After that the ignition and operation of the burner are automatically controlled until the operation of the burner is terminated by manually turning the main control valve 4 from the on position to the off position. As the main control valve 4 is turned from the off position to the on position the master switch 23 is closed by the cam 25 and lever 24. After the main control valve has been opened gas can flow from the manifold M through the main control valve 4 and into the chamber 38 of the safety control valve mechanism 5, the various parts of which are in the position shown in Fig. 2. But the gas can go no further since the valve 43 is seated, thus closing the passageway 41, the only exit from the chamber 38. As soon as the switch 23 is closed current flows from one side 100 of the line through the leads 101 and 112 to the terminal 82 and thence through the conductor bar 84 to the terminal 83. From the terminal 83 the current flows through the leads 113 and 114 and the

switch 92 which is locked in closed position to the terminal 88 of the normally closed switch 21, and thence through the conductor bar 91 to the terminals 89 and 90. From the terminal 89 the current flows through the lead 115 to the electrical resistance ignition element 18, thence through the ignition element 18 and back to the other side 105 of the line through the leads 116 and 106, thus completing a circuit through the ignition element 18 which energizes it and renders it operable to ignite the pilot burner 16 as soon as gas is supplied thereto. From the terminal 90 of the normally closed switch 21 the current flows through the lead 117 to the solenoid 22, thence through the winding of the solenoid and back to the other side 105 of the line through the leads 118 and 106, thus completing a circuit which energizes the solenoid 22. The energization of the solenoid 22 causes it, through the lever 56, to shift the various parts of the safety control valve mechanism from the position shown in Fig. 2 to the position shown in Fig. 3. In this position the valve 43 is held away from the valve seat 44 and is held against the ends of the legs of the magnet 72. This allows gas to flow from the chamber 38 into the chamber 40 and thence through the port 80 and conduit 17 to the pilot burner 16 where it is ignited by the ignition element 18. But the gas cannot yet flow to the main burner 1 since the valve 45 is being held against the seat 46 which cuts off communication between the chamber 40 and the chamber 39. As soon as the pilot burner 16 is ignited it projects a flame against and heats both the thermocouple 20 and the thermostatic element 19. The heating of the thermocouple 20 generates a minute current which energizes the electromagnet 72 sufficiently for it to hold the valve 43 in the position shown in Fig. 3, after the valve 43 has been moved into engagement with the magnet 72 by the solenoid 22. But the magnet 72 when energized by the thermocouple 20 is not strong enough to attract and withdraw the valve 43 from the position shown in Fig. 2 to the position shown in Fig. 3. It can only hold it in this position after it has been moved thereto by the solenoid 22 through the medium of the lever 56. The electric circuit between the thermocouple 20 and the winding 75 of the magnet 72 is through the copper tube 26 and the wire 27. This circuit will be maintained as long as the thermocouple is heated. After the thermostatic element 19 has been heated sufficiently, which is after the thermocouple has energized the electromagnet 72, it will open the normally closed switch 21, breaking the circuit to and de-energizing both the ignition element 18 and the solenoid 22. After the pilot burner has been ignited there is no further need to maintain the ignition element energized. As soon as the solenoid 22 is de-energized the spring 70 will return the lever 56 and valve 45 back from the position shown in Fig. 3 to the position shown in Fig. 2. The valve 43 will be held in the position shown in Fig. 3 by the electromagnet 72, the elongated slot 62 in the valve stem 47 being provided for this purpose. Communication is then established between the chambers 38 and 39 through the chamber 40. Gas will then flow from the chamber 38 into the chamber 40 and then into the chamber 39. From the chamber 39 gas will flow through the oven temperature control valve 6 and conduit 3 to the main burner 1 where it will be ignited by the pilot burner 16. The apparatus is now operating normally, and in the absence of any abnormal conditions it will continue to do so, provided the pilot burner remains ignited, until the supply of gas to both the

pilot burner and the main burner is cut off by the manual closing of the main control valve 4.

In the event the pilot burner 16 is extinguished for any reason during operation, the thermocouple 29 will cool in a few seconds and de-energize the magnet 72. The de-energization of the magnet 72 will release the valve 43 which will then drop back into engagement with the valve seat 44, as shown in Fig. 2, which will cut off the flow of gas from the chamber 38 into the chambers 40 and 39, and from them to the pilot light 16 of the main burner 1. The burner 1 will then be extinguished along with the pilot burner. As soon as the thermostatic element 19 cools it will close the switch 21 which will energize both the ignition element 18 and the solenoid 22 as previously described since the main control valve 4 is still open and the switch 23 is closed. The pilot burner 16 will then be re-ignited and the rest of the apparatus will again function as described, provided there is gas available. If no gas is available everything will remain in condition to ignite the pilot burner and re-initiate operation as soon as gas is again available. In the event of either a momentary or prolonged power failure during operation, the apparatus will continue to operate normally until terminated by the manual closing of the main control valve, provided of course that all other conditions are normal. In order to operate the apparatus during a prolonged power failure which occurred prior to operation, it is only necessary to hold a match to the pilot burner 16 and manually move the lever 56 from the position shown in Fig. 2 to the position shown in Fig. 3 and hold it in this position a sufficient time for the thermocouple 29 to become heated. A pull rod and button 120 and 121 connected to the lower end of the core 66 of the solenoid 22 are provided for this purpose. After the thermocouple has been heated the pull rod 120 may be released after which the spring 70 will return the lever 56 and valve 45 to their initial positions as shown in Fig. 2. The apparatus will then continue to function normally as described under the control of the pilot burner 16 and the oven temperature control valve 6.

When the apparatus is used in conjunction with the time control mechanism 109 the time control mechanism is set to initiate operation of the main burner 1 at a predetermined time and to terminate operation thereof at a predetermined later time. The setting of the time control mechanism 109 opens the switches 92 and 96 as shown in Fig. 5. Operating current is supplied to the time control mechanism from the line 100-105 by the leads 101 and 106. After the time control mechanism has been set the main control valve 4 is manually opened which closes the master switch 23. Then at the predetermined set time the time control mechanism will close the supplemental switch 92 and establish the circuits to the ignition element 18 and the solenoid 22. The apparatus will then operate as previously described until the time control mechanism terminates operation by opening the switch 22 and closing the switch 96. The closing of the switch 96 energizes the solenoid 5 which then closes the valve V. The closing of the valve V cuts off the supply of gas to and extinguishes the pilot burner 16. After the pilot burner 16 has been extinguished the thermocouple 29 cools which deenergizes the electro-magnet 72. The safety control valve mechanism 5 will then operate as previously described to cut off the supply of gas to the main burner, thus terminating the operation thereof. The main

control valve 4 can then be manually closed at any time.

From the foregoing it will be apparent to those skilled in this art that we have provided a very simple and efficient means for accomplishing the objects of our invention; and it is to be understood that we are not limited to the specific constructions shown and described herein as various modifications may be made thereto within the scope of the appended claims.

What is claimed is:

1. In a device of the character described, the combination of a cup shaped upper casing having a transverse wall intermediate the ends thereof, an opposing cup shaped lower casing, a partition bolted between said upper and said lower casings, said upper casing and said partition defining a first chamber and a third chamber and said lower casing and said partition defining a second chamber, a gas inlet port into said first chamber and a gas outlet port from each of said second and said third chambers, a first passageway and a second passageway through said partition, said first passageway extending between said first chamber and said second chamber and said second passageway extending between said second chamber and said third chamber, a first valve and a second valve, said first valve being operative to open and close said first passageway and said second valve being operative to open and close said second passageway, a solenoid secured to the outer face of the bottom wall of said lower casing, and operative connections between said solenoid and said valves through which said solenoid when energized simultaneously shifts said valves to open said first passageway and to close said second passageway.

2. In a device of the character described, the combination of a cup shaped upper casing having a transverse wall intermediate the ends thereof, an opposing cup shaped lower casing, a partition bolted between said upper and said lower casings, said upper casing and said partition defining a first chamber and a third chamber and said lower casing and said partition defining a second chamber, a gas inlet port into said first chamber and a gas outlet port from each of said second and said third chambers, a first passageway and a second passageway through said partition, said first passageway extending between said first chamber and said second chamber and said second passageway extending between said second chamber and said third chamber, a first valve and a second valve, said first valve being operative to open and close said first passageway and said second valve being operative to open and close said second passageway, a solenoid secured to the outer face of the bottom wall of said lower casing, operative connections between said solenoid and said valves through which said solenoid when energized simultaneously shifts said valves to open said first passageway and to close said second passageway, and means operative to hold said first valve in open position and to return said second valve to open position after said solenoid has been de-energized.

3. In a device of the character described, the combination of a cup shaped upper casing having a transverse wall intermediate the ends thereof, an opposing cup shaped lower casing, a partition bolted between said upper and said lower casings, said upper casing and said partition defining a first chamber and a third chamber and said lower casing and said partition defining a second chamber, a gas inlet port into said first chamber and

a gas outlet port from each of said second and said third chambers, a first passageway and a second passageway through said partition, said first passageway extending between said first chamber and said second chamber and said second passageway extending between said second chamber and said third chamber, a first valve and a second valve, said first valve being operative to open and close said first passageway and said second valve being operative to open and close said second passageway, a solenoid secured to the outer face of the bottom wall of said lower casing, operative connections between said solenoid and said valves through which said solenoid when energized simultaneously shifts said valves to open said first passageway and to close said second passageway, and an electromagnet in said first chamber operative when energized to hold said first valve in shifted position after said solenoid has been de-energized.

4. In a device of the character described, the combination of a cup shaped upper casing having a transverse wall intermediate the ends thereof, an opposing cup shaped lower casing, a partition bolted between said upper and said lower casings, said upper casing and said partition defining a first chamber and a third chamber and said lower casing and said partition defining a second chamber, a gas inlet port into said first chamber and a gas outlet port from each of said second and said third chambers, a first passageway and a second passageway through said partition, said first passageway extending between said first chamber and said second chamber and said second passageway extending between said second chamber and said third chamber, a first valve and a second valve, said first valve being operative to open and close said first passageway and said second valve being operative to open and close said second passageway, a solenoid secured to the outer face of the bottom wall of said lower casing, operative connections between said solenoid and said valves through which said solenoid when energized simultaneously shifts said valves to open said first passageway and to close said second passageway, and means in said second chamber operative to shift said second valve back to open position after said solenoid has been de-energized.

5. In a device of the character described, the combination of a cup shaped upper casing having a transverse wall intermediate the ends thereof, an opposing cup shaped lower casing, a partition bolted between said upper and said lower casings, said upper casing and said partition defining a first chamber and a third chamber and said lower casing and said partition defining a second chamber, a gas inlet port into said first chamber and a gas outlet port from each of said second and said third chambers, a first passageway and a second passageway through said partition, said first passageway extending between said first chamber and said second chamber and said second passageway extending between said second chamber and said third chamber, a first valve and a second valve, said first valve being operative to open and close said first passageway and said second valve being operative to open and close said second passageway, a solenoid secured to the outer face of the bottom wall of said lower casing, operative connections between said solenoid and said valves through which said solenoid when energized simultaneously shifts said valves to open said first passageway and to close said second passageway, an electromagnet in said first chamber operative when energized to hold said first valve in open position after said solenoid has been de-energized, and spring means in said second chamber operative to rock said lever to shift said second valve back to open position upon the de-energization of said solenoid.

chamber operative when energized to hold said first valve in open position after said solenoid has been de-energized, and spring means in said second chamber operative to shift said second valve back to open position after said solenoid has been de-energized.

6. In a device of the character described, the combination of a cup shaped upper casing having a transverse wall intermediate the ends thereof, 10 an opposing cup shaped lower casing, a partition bolted between said upper and said lower casings, said upper casing and said partition defining a first chamber and a third chamber and said lower casing and said partition defining a second chamber, 15 a gas inlet port into said first chamber and a gas outlet port from each of said second and said third chambers, a first passageway and a second passageway through said partition, said first passageway extending between said first chamber and said second chamber and said second chamber and said third chamber, a first valve and a second valve, said first valve being operative to open and close said first passageway and 20 said second valve being operative to open and close said second passageway, a pivoted lever in said second chamber pivotally connected to each of said valves, and a solenoid secured to the outer surface of the bottom wall of said lower casing 25 connected to said lever and operative when energized to rock said lever to simultaneously shift said valves to open said first passageway and to close said second passageway.

7. In a device of the character described, the combination of a cup shaped upper casing having a transverse wall intermediate the ends thereof, 30 an opposing cup shaped lower casing, a partition bolted between said upper and said lower casings, said upper casing and said partition defining a first chamber and a third chamber and said lower casing and said partition defining a second chamber, a gas inlet port into said first chamber and a gas outlet port from each of said second and said third chambers, a first passageway and a second passageway through said partition, said first passageway extending between said first chamber and said second chamber and said second passageway extending between said second chamber and said third chamber, a first valve 35 and a second valve, said first valve being operative to open and close said first passageway and said second valve being operative to open and close said second passageway, a pivoted lever in said second chamber pivotally connected to each of said valves, a solenoid secured to the outer surface of the bottom wall of said lower casing 40 connected to said lever and operative when energized to rock said lever to simultaneously shift said valves to open said first passageway and to close said second passageway, an electromagnet in said first chamber operative when energized to hold said first valve in open position after said solenoid has been de-energized, and spring means in said second chamber operative to rock said lever to shift said second valve back to open position upon the de-energization of said solenoid.
